UNITED STATES PATENT OFFICE.

RICHARD D. NILEON, OF DENVER, COLORADO.

FIRE ESCAPE.

Application filed June 24, 1921. Serial No. 480,061.

To all whom it may concern:

Be it known that I, RICHARD D. NILEON, a citizen of the United States, residing at Denver, in the State of Colorado, have invented certain new and useful Improvements in a Fire Escape, of which the following is a specification.

This invention relates to improvements in collapsible fire escapes and more particularly to an improved apparatus having the general appearance of a rocking chair and constructed to include a collapsible ladder which may be quickly opened and thrown out of a window to be placed in operative position on the side of the building when a fire occurs.

One of the objects of the invention is to provide a fire escape which will, ordinarily be used as a chair, and which may be the means of saving lives during a fire by permitting the occupants of a building to descend from an open window, easily and quickly and with a minimum danger.

Another object of the invention is to provide a collapsible fire escape which may be quickly opened and thrown into an operative position, the various parts which are unessential to the fire escape when in use, automatically dropping from the structure so that a complete ladder will be formed, hung from a windowsill and properly spaced from the wall of a building to permit the user to gain a foot hold on the ladder rung.

Other objects of the invention will appear upon consideration of the following detail description and accompanying drawings, wherein:

Figure 1 is a perspective view of the apparatus constructed in accordance with my invention, and showing the general appearance of a rocking chair which entirely contains the device.

Figure 2 is a detail view of a cloth bag or hood adapted to fit over the back of the chair to enclose some of the structure.

Figure 3 is a perspective view of the drum upon which the ladder is wound,

Figure 4 is a side view of the fire escape in operative position,

Figure 5 is a front elevation of the same,

Figure 6 is a cross section through the apparatus before being opened,

Figure 7 is a detail view of the end of one of the frame members,

Figure 8 is a perspective view of the meet-

ing ends of the front and bottom frame members,

Figure 9 is a cross section showing the pivoting means for the frame members, and

Figure 10 is a perspective view showing one of the ladder rungs shaped in accordance with the structure incorporated in the invention.

Referring to the drawing by numerals, the back of the chair consists of two elongated frame members 1, the terminals being connected to a cross rod 2 which acts as a connecting pivot for the links 3, the terminals of which are connected to retaining hooks 4. The lower ends of the frame members 1 are connected by the pivot rod 5 to the frame members 6 which form the rockers for the chair, the pivot member 5 being approximately midway between the ends of the rockers. The forward end of the rockers 6 is connected to a front frame bar 7 by a pivot rod 8 and the lower end of each frame bar 7 is equipped with an abutment lug 9 adapted to engage the upper edge of the rocker as shown in Fig. 8, to limit the backward swinging movement of the frame member 7 so that the frame member will be held in the proper relative position with respect to the rocker 6. The upper ends of the front frame bars 7 are pivotally connected by the pivot rod 10 to the top frame bars 11 which support the seat of the rocker and the lower edges of the frame bars 11 are provided with notches 12 forming hooks adapted to be caught over the retaining rod 13 placed approximately midway the ends of the back frame bars 1 as shown to advantage in Fig. 6 of the drawing. Midway the rods 2 and 13 is another rod 14 against which the ends of the hooks 4 are engaged when the device is in inoperative position. Mounted upon the frame bars 11 is a sheet of suitable material which may be metal or any other kind of material forming a seat 15 and this is provided with a hook member 16 adapted to be caught over the rod 13 to maintain the seat 15 in place. A front panel 16' covers the front of the chair and rests against the front frame bars 7, the upper edge of the panel 16 being pivotally connected to the seat 15 so that these two parts 15 and 16 are pivotally connected together and are snugly fitted between the front and top frame bars 7 and 11 respectively to form a neat structure and give an attractive ap-

pearance to the chair when it is in the form shown in Fig. 1 of the drawing.

The bottom of the chair directly beneath the seat 15 and between the rockers 6 is provided with a bottom panel 17, the forward edge being hooked over the pivot rod 8 to maintain the panel in position, the rear edge of the panel resting upon the cross pivot rod 5. The back of the chair is provided with a back panel 18 extending throughout the length of the back frame bars 1, the opposite longitudinal edges being notched as indicated at 19 to admit the ends of the top frame bars 11. The back panel 18 extends between the back frame bars 1 and the top edge is provided with suitable connections with the top pivot member 2 so that the panel will be held in position while the chair is in use, but which will permit the panel to readily drop off when the apparatus is thrown into operative position. The sides of the chair are closed by the two side panels 20 shown in detail in Fig. 3 and forming the ends of a reel which includes the reel rods 21 attached to the circular end pieces 22 which are secured to the side panels 20. This structure forms a reel upon which the flexible rope ladder 23 is wound loosely. The rope ladder consists of parallel strands of wire cable or rope, attached at regular intervals to the rungs 24 of the ladder, the terminals of which are provided with right angularly projecting prongs 25 the terminals of which are pointed to engage the wall of the building as shown in the drawing whereby the rungs of the ladder are held away from the wall to permit the user to gain a good foot hold on the ladder rungs when he is descending. The terminals of the cable or rope forming the ladder are connected to the rear ends of the top frame bars 11 as indicated at 26 and the ladder is wound around the reel in a manner that will permit it to quickly and easily unwind when the device is opened.

When the apparatus is in folded position to form the chair, the back and hook members 4 with the links 3 are covered by a cloth covering in the form of a bag or casing 28 which is provided with straps 29 and 30 adapted to be secured together to maintain the cover in position. When the chair is opened or unfolded, the bag or cover 28 will be removed and the straps may be

connected thereby serving as handles to permit the user of the fire escape to carry a child down the ladder by placing the child in the bag which, of course, will be for this purpose. When the device is to be used, the chair will be thrust out of a window and the hooks 4 will be caught under the windowsill in the interior of the room, the links 3 resting upon the top of the windowsill as shown in Fig. 4. The hook members 12 will then be disconnected from the rods 13 and the frame structure, being pivotally connected at the ends of the frame pieces will drop to the elongated position shown in Fig. 4 while the reel will continue to unwind and drop to the ground the ladder dropping out in the proper form to serve as a descending ladder. While this is occurring the panels forming the chair covering will entirely drop from the structure leaving nothing but the essential portions of the ladder structure.

It will be apparent from the above that the apparatus will present a neat appearance and may be used as a comfortable chair, while at the same time, it may be quickly thrown into operative position for use as a fire escape thus serving to save the lives of persons occupying a burning building, when other means of escape is cut off.

Minor changes may be made in the details of construction without departing from the spirit of the invention or the scope of the claim hereunto appended.

What is claimed is:—

A device of the class described comprising an elongated frame structure adapted to form a chair, said frame including a series of pivotally connected frame bars, loosely connected panels mounted upon the frame structure, hook members mounted on the frame structure to support the same from a window sill, said structure including side panels, cross arms extending transversely between the panels and connected thereto to form a reel, and a flexible ladder attached to the ends of two of the frame bars and normally wound upon the said reel and adapted to unwind therefrom when said structure is open.

In testimony whereof, I have affixed my signature.

RICHARD D. NILEON.
